DESIGN FOR A GAUGE DIAL OR SIMILAR ARTICLE

Carl H. Graesser, Southport, and Joseph V. Tracy,
Fairfield, Conn., assignors to Manning, Maxwell
& Moore, Incorporated, New York, N. Y., a cor-
poration of New Jersey

Application October 30, 1940, Serial No. 96,201

Term of patent 7 years

To all whom it may concern:

Be it known that we, Carl H. Graesser and Joseph V. Tracy, citizens of the United States of America, residing at Southport and Fairfield, respectively, in the county of Fairfield and State of Connecticut, have invented a new, original, and ornamental Design for a Gauge Dial or Similar Article, of which the following is a specification, reference being had to the accompanying drawing, forming a part thereof.

Fig. 1 is a front view of a gauge dial embodying our new design; and

Fig. 2 is an edge view thereof.

We claim:

The ornamental design for a gauge dial or similar article, substantially as shown.

CARL H. GRAESSER.
JOSEPH V. TRACY.
